UNITED STATES PATENT OFFICE

ROBERT M. WHITSON, OF LA GRANGE, ILLINOIS

DESIGN FOR A SIGN

Application filed May 10, 1933. Serial No. 48,065. Term of patent 7 years.

To all whom it may concern:

Be it known that I, ROBERT M. WHITSON, a citizen of the United States, residing at La Grange, in the county of Cook and State of Illinois, have invented a new, original, and ornamental Design for Sign, of which the following is a specification, reference being had to the accompanying drawing, forming part thereof.

The single figure in the drawing shows a front elevational view of the sign of applicant's design.

The sign is relatively thin and flat.

I claim:

The ornamental design for a sign, as shown, and described.

ROBERT M. WHITSON.
